UNITED STATES PATENT OFFICE.

JOHN BAILEY, OF CARPENTERSVILLE, ILLINOIS, ASSIGNOR TO THE ILLINOIS IRON AND BOLT COMPANY, OF SAME PLACE.

HYDRAULIC PRESS.

SPECIFICATION forming part of Letters Patent No. 366,367, dated July 12, 1887.

Application filed September 16, 1886. Serial No. 213,735. (No model.)

To all whom it may concern:

Be it known that I, JOHN BAILEY, a citizen of the United States, and residing at Carpentersville, in the county of Kane and State of Illinois, have invented a certain new and useful Improvement in Hydraulic Presses, which is fully set forth in the following specification, reference being had to the accompanying drawings, in which—

10 Figure 1 is a plan view of a hydraulic press embodying my invention; Fig. 2, a sectional view of the same, taken on the line $x-x$ of Fig. 1, and looking in the direction of the arrow 1; Fig. 3, a sectional view taken on the line $y-y$ of Fig. 1 and looking in the direction of the arrow 2; Fig. 4, a sectional view taken on the line $z-z$ of Fig. 1 and looking in the direction of the arrow 3; Fig. 5, a plan section taken on the line $v-v$ of Fig. 4, and Fig. 6 a detail plan section of the piston.

Like letters refer to like parts in all the figures of the drawings.

My invention relates to hydraulic presses, and has for its object to produce a press which shall be compact in the arrangement of its parts and of large capacity in proportion to the space occupied; also, to produce a press having various improved features to increase its efficiency of operation.

30 To these ends my invention consists in certain novel features, which I will now proceed to describe, and will then particularly point out in the claims.

In the drawings, A represents the reservoir or cistern, which is preferably cylindrical in form, and B the cylinder, also cylindrical in form and arranged centrally within the reservoir A. In the present instance these two parts are shown formed in a single casting 35 united to a base, A', which forms the bottom of the reservoir and the head of the cylinder. The cylinder B is shown as extending upward some distance above the reservoir and provided with a shoulder, b, upon which and upon 40 the upper edge of the reservoir a cover, A'', rests, the said cover closing the open upper end of the reservoir, as shown.

C represents the piston, which consists of a series of radial plates or arms, c, forming at 45 their central junction a hub, c', the said piston being provided at its upper end with the usual follower or pressing-table, C', and at its

lower end with a piston-head, C'', of any approved construction, the said head being shown in the present instance as provided with a washer, C'', of leather or other suitable material, inserted in its under side and secured in position by means of a screw-bolt, c''. The plates or arms c are each provided with a groove or notch, c'', in their outer edge at a point a short distance above the piston-head C'' for the purposes hereinafter stated. A passage, b', is formed through the cylinder-wall at the top of the reservoir A, the said passage establishing a communication between the interior of the cylinder above the piston-head and the reservoir. Only one of these passages is shown in the present instance, but a greater number may be employed, if desired.

D represents the pump, which may be a force-pump of any suitable construction bolted directly to the outer wall of the reservoir A, which is provided at this point with a suitable projecting seat, A'', to form a plane surface against which the pump may be held. 75 In the present instance I have shown the pump as provided with a plunger, D', working in a suitable chamber provided with the usual valves, d and d', as shown, the said chamber communicating at one end with a passage, D'', leading to the interior of the reservoir A, and at the other end with a passage, D'', leading to the bottom of the cylinder B, with the interior of which it communicates at this point. The plunger D' is operated by means of a lever, E, 80 pivoted upon a standard, E', attached to the body of the pump, as shown, and having pivoted to it the upper end of the link E'', the lower end of which is pivoted to the head of the plunger.

Above the passage D'' is arranged a bridge, F, extending from the reservoir-wall to the cylinder-wall, in which bridge the trip-valve is mounted. This valve is shown at G in the several figures of the drawings, its stem G' extending upward through a cylindrical passage, f, in the bridge F, within which passage it fits snugly, being made a ground-fit within the same. Near the upper portion of the bridge F the passage f communicates with a discharge-aperture, f', leading to the reservoir A. The valve-stem G' is, as heretofore stated, first made a ground-fit for its entire length above the valve and the discharge-aperture, and is

then provided with a series of grooves, g , as shown more particularly in Figs. 4 and 5 of the drawings, the said grooves extending from the valve to the discharge-aperture, and the 5 stem above that point retaining its cylindrical shape, as shown. The trip-valve is operated by means of a lever, H , the extremity of which is pivoted to the upper end of the valve stem, as shown, the lever being pivoted to a suitable 10 fulcrum, H' or H'' . These fulcrums are shown as arranged on each side of the upper extremity of the valve-stem, and the lever may be fulcrumed upon either one of them, as desired, to permit the lever to be operated 15 from either side. It will be understood, of course, that a suitable slot will be provided in the lever either at the point of its connection with the fulcrum or with the valve-stem in order to permit this latter to move vertically without lateral straining. The lever H will, in practice, be made of sufficient weight to hold the valve normally in the position shown—that is to say, against the seat. A 20 filling-aperture, I , closed by a suitable plug or cap, is formed in the top or covering A' , in order to permit the reservoir to be filled without removing the said cover.

The operation of my hydraulic press may be readily understood from the preceding description. The reservoir A is first filled with some suitable liquid—such, for example, as oil, which I prefer, water, or the like. In filling the reservoir, when the oil reaches the height of the aperture b' , it will overflow into 30 the cylinder, and the filling may be continued until the oil stands on the same level in the cylinder above the piston therein as it does in the reservoir. The pump-chamber will of course be filled at the same time. By this means it 35 will be seen that the cylinder is employed as a partial reservoir, thus enabling me to diminish the size of the reservoir proper and consequently reduce the space occupied by the whole apparatus. The construction of the 40 piston C with the radial plates or arms c forms a series of spaces above the piston-head, which is occupied by the oil, a free communication 45 between these spaces being established by means of the grooves c' , by reason of which 50 construction they all communicate with each other and with the reservoir through the passage b' .

Of course a central piston of small diameter might be employed as a substitute for the construction shown; but I prefer this latter on account of its superior strength and durability. Upon operating the pump the oil is forced into the cylinder B underneath the piston-head to operate the pump in the usual manner. As the 55 piston-head and piston rise the oil above the head will flow back in the reservoir through the passage b' , thus supplying the reservoir to compensate for the loss of the oil drawn therefrom by the pump. Another function of the 60 passage b' is to prevent the piston and its parts from being forced entirely out of the cylinder, since when the piston-head reaches the level

of the passage b' it cannot be forced up any higher, owing to the escape of oil underneath it through the said passage.

When it is desired to lower the piston, the lever H is raised, thereby lowering the valve G from its seat, when the oil will pass up around the said valve and along the passage f by means of the grooves g in the valve-stem until it reaches the discharge-aperture f'' , through which it will pass to the reservoir. Since the grooves g terminate at this discharge-aperture, the oil cannot leak past this point, but must pass through the discharge-aperture, being prevented from rising above the same by the cylindrical upper portion of the valve-stem, which fits snugly within the upper portion of the passage f .

It will be at once seen that by arranging the cylinder within the reservoir I am enabled to greatly economize space by reason of the compactness of this arrangement, this economy being increased by mounting the pump directly upon the side of the reservoir, as shown and described. Moreover, this arrangement of the cylinder within the reservoir enables me to more readily connect the two, so as to utilize the cylinder as an auxiliary reservoir, as hereinbefore described.

It is obvious that various modifications in the details of construction and arrangement of the parts may be made without departing from the principle of my invention and I therefore do not wish to be understood as limiting myself strictly to the precise details hereinbefore described, and shown in the drawings.

Having thus described my invention, what I claim as new, and desire to secure by Letters Patent, is—

1. In a hydraulic press, the combination, with the reservoir, of the cylinder, the piston arranged therein and provided with spaces to form in conjunction with the upper portion of the cylinder an auxiliary reservoir, and a passage leading from the said spaces to the reservoir, substantially as and for the purpose specified.

2. In a hydraulic press, the combination, with the cylinder and the reservoir surrounding the same, of the piston arranged in the cylinder and provided with spaces to form in conjunction with the upper portion of the cylinder an auxiliary reservoir above the piston-head, and a passage leading from the reservoir through the cylinder into the said spaces above the piston-head, substantially as and for the purposes specified.

3. In a hydraulic press, the reservoir and the cylinder provided with a passage through its upper portion communicating therewith, in combination with the piston provided with head C' , radial plates c , and hub c' , said plates having communicating grooves or notches c' , substantially as and for the purposes specified.

JOHN BAILEY.
